(57) **CLAIM**

What is claimed is the ornamental design for a locator safety spacer clip, as shown and described.

DESCRIPTION

FIG. 1 is a perspective view of a locator safety spacer clip, showing the new design;

FIG. 2 is a front elevational view thereof, the rear elevational, left-side elevational, and right-side elevational views all being a mirror image thereof;

FIG. 3 is a top plan view thereof;

FIG. 4 is a bottom plan view thereof; and,

FIG. 5 is a cross-sectional view thereof, taken generally along lines 5-5 of FIG. 2.
